SHIP LIGHT

George Chauncey Parsons, Long Beach, Calif.

Application October 29, 1943, Serial No. 508,166

2 Claims. (Cl. 240—7.5)

This invention relates to improvements in lamps and particularly relates to improvements in ship lamps.

An object of the invention is to provide a simplified type of ship lamp in which the lens of the lamp is retained securely but without being subjected to stresses that might tend to crack or break the lens.

Another object of the invention is to provide a ship lamp formed of relatively few parts which are readily produced and can easily be removed and replaced when it is necessary to repair the lamp.

A further object of the invention is to provide a ship lamp in which the lens retaining portions are integral with the cover and the base of the lamp and so arranged that the lens can be removed easily for cleaning or replacement.

Other objects of the invention will become apparent from the following description of a typical form of ship lamp embodying the present invention.

Generally, lamps embodying the present invention are characterized by a stamped or spun metal cover and base formed of a plurality of shells having inturned, grooved flanges in opposed relationship for receiving and retaining the lens of the lamp. The grooves in the flanges preferably are somewhat wider than the thickness of the edges of the lens in order to permit relative expansion and contraction of these elements without subjecting the lens to excessive stresses. The base and cover of the lamp may be retained in spaced apart, and clamping relation to the lens by means of the rods which, together with suitably spaced rings, form a protective cage for the lens.

The relationship of the lens, the base and the cover is such that the lens-receiving grooves can be provided with suitable gaskets or caulking to render the joints between these elements watertight to protect the light therein.

For a better understanding of the present invention, reference may be had to the accompanying drawing in which the single figure is a view in side elevation and partly in vertical section of a typical form of ship lamp embodying the present invention.

The ship lamp chosen for illustrating the present invention includes a base 10, a cover 11, a lens 12 therebetween and a lamp base and socket 13 mounted on the base 10. The lens 12 is protected by means of a cage 14 interconnecting the cover 11 and the base 10.

The base 10 of the lamp includes two shells 15 and 16 formed, preferably, of sheet metal by

stamping, spinning or in any other suitable way. The shell 15 is generally cup-shaped having a flat disc-like base 17, a cylindrical wall portion 18 and a radially extending flange 19 at the upper edge of the wall portion 18.

The shell 16 has a base flange 20 overlying the flange 19 of the shell 15, a generally upwardly tapered wall portion 21 and an inwardly directed flange 22 provided with an annular groove 23 for receiving the lower end of the tubular "Fresnel" type of lens 12. While a circular tubular lens is illustrated, it will be understood that lenses of other shapes may be used, for example, square, triangular, or partially curved and partially flat.

15 The cover 11 of the lamp includes a pair of shells 24 and 25, preferably formed of metal by stamping or spinning. The upper shell 24 is generally dome-like or concavo-convex and has a centrally located access opening 26 in its top in which is secured, by soldering or welding, an internally threaded annular ring 27.

15 The cover 11 of the lamp includes a pair of shells 24 and 25, preferably formed of metal by stamping or spinning. The upper shell 24 is generally dome-like or concavo-convex and has a centrally located access opening 26 in its top in which is secured, by soldering or welding, an internally threaded annular ring 27.

20 A U-shaped handle 28 for the lamp has its ends secured in a disc-like plate 29 forming a closure for the access opening 26. The plate 29 is provided with a flange 30 overlying the ring 27 and an internally threaded collar 31 threaded into the ring 27. A gasket 32 may be interposed between the flange 30 and the ring 27 to render the closure watertight.

20 The shell 24 is provided with a flange 33 at its lower edge that overlies a similar flange 34 at the upper edge of the generally conical, downwardly tapering wall 35 of the shell 25. At the lower edge of the wall 35 is an inwardly directed flange 36 having an annular groove 37 therein for receiving loosely the upper edge of the lens 12.

25 In order to retain the shells 15, 16 and the shells 24 and 25 together and in retaining relationship to the lens 12, the cage 14 is formed of a plurality of vertically extending rods 38 having threaded end portions 38a and 38b that project through aligned apertures 39 in the flanges of the shells 15, 16, 24 and 25. The threaded portions 38a and 38b receive the nuts 40 above and below the flanges on the shells and permit adjustment of the spacing of the base 10, the cover 11, as well as clamping the flanges together. In order to render the joints between the flanges 18 and 20 and the flanges 33 and 34 watertight, the ring gaskets 41 may be interposed between the flanges.

30 The lens 12 may be sealed in watertight relationships to the flanges 22 and 36 by means of a packing 42 of a suitable caulking composition, for example, litharge and glycerine, pressed into

35

the grooves 23 and 37 outwardly of the lens 12 or by means of a suitable gasket formed of rubber or other comparable material (not shown) between the flanges 22 and 36 and the ends of the lens 12.

The above described mounting for the lens affords substantial protection for the lens 12 and permits adjustment of the cover 11 and base 10 to accommodate their spacing to lenses of different lengths. Moreover, a certain freedom of expansion and contraction of the various elements is permitted, thereby relieving the lens of stresses that might cause it to break.

The lens 12 may be protected further by means of the rings 44 of wire or metal rod that are supported within the rods 38 by means of the clips 45. These clips include a center band portion 45a bent partially around the rods 38 and end band portions 45b that are bent around the rings 44 on opposite sides of the rods 38. If desired, the clips 45 may be welded or soldered to the rods 38 and the rings 44 of the cage 14.

The light source for the lamp may be of any desired type, for example, an oil lamp or an electric light. In the form of the invention illustrated, the ship lamp is provided with an electric bulb 46 supported in the base and socket portion 13. If an oil lamp is used, the base and socket portion 13 and the bulb 46 are omitted and a detachable oil lamp and chimney are substituted therefor and proper ventilating openings and a suitably baffled flue are provided. The flue may be mounted on or substituted for the plate 29.

The base and socket portion 13 may include a cup-shaped shell 47 formed of insulating material, having a base flange 47a that is secured to the base 17 of the shell 15 by means of screws 48 or bolts. The socket 49 for the bulb 46 may be of conventional type and is secured to the top of the shell 47.

The provision of the removable plate 29 for closing the access opening 26 permits ready removal and insertion of the lamp bulb 46 without taking down the entire lamp.

The wiring for the socket 49 may pass through an opening in the shell 47 and a gland 50 in the wall 18 of the base shell 15. The gland 50 is packed to render it watertight so that leakage around the gland or between the gland and the wiring is prevented.

The lamp may be provided with lashing rings 51, if desired. These rings 51 are retained on the lamp by means of the U-clips 52 straddling the flanges 19, 20 and the flanges 33 and 34. The

clips 52 have apertures therein for receiving the rods 38. The nuts 40 engage the outer surfaces of the clips 52 and lock them in position.

The above described ship lamp is simple to produce, is sturdy, and the provision of the separable shells making up the base 10 and cover 11 of the lamp permits the formation of the inwardly projecting flanges for receiving the lens 12. Inasmuch as the cover and base project outwardly beyond the lens 12, additional protection is afforded the lens and additional space is provided to allow for relative expansion and contraction of the parts. Moreover, every element of the lamp can be detached and replaced, if damaged, without requiring replacement of other associated, undamaged parts.

It will be understood, of course, that the lamps can be modified considerably in the shape and size of the parts. Therefore, the above-described embodiment of the invention should be considered as illustrative of the invention and not as limiting the scope of the following claims.

I claim:

1. A ship lamp comprising a base having a bottom shell provided with substantially flat, disc-like bottom, an upwardly extending annular sidewall and an outwardly extending flange at the upper edge of said side wall and a second annular shell having an outwardly extending flange overlying the flange on said bottom shell, an upwardly tapered side wall, and an inwardly extending flange at its upper edge; a cover having a dome-shaped top shell provided with an outwardly extending flange at its edge and an aperture in its center zone, a detachable closure member for said aperture, and another annular shell having an outwardly extending flange underlying the flange in said top shell, a downwardly tapered side wall, and an inwardly extending flange at its lower edge; a tubular lens interposed between said inwardly extending flanges; means forming grooves in said inwardly extending flanges for receiving the ends of said lens; and means extending through and between the outwardly extending flanges for clamping said flanges of said base shells together, clamping the flanges of said cover shells together, and retaining said cover and base in spaced apart relation to retain said lens in said grooves.

2. The ship lamp set forth in claim 1, in which said detachable closure is provided with a handle for supporting said lamp.

GEORGE CHAUNCEY PARSONS.
